CLAIM

The ornamental design for a type font, as shown and described.

DESCRIPTION

FIG. 1 is a face view of a first embodiment of a type font showing my new design with respect to the numbers 0-9 as well as miscellaneous characters that may be found upon a conventional computer keyboard wherein neither small nor large inserts are included;

FIG. 2 is a face view of a second embodiment of the type font shown in FIG. 1, the difference being that both small and large inserts are included; and,

FIG. 3 is a face view of a third embodiment of the type font shown in FIG. 1, the difference being that only small inserts are included.
